(57) **CLAIM**

The ornamental design for a Patmas weave stent, as shown and described.

DESCRIPTION

FIG. 1 is a perspective frontal view of a Patmas weave stent showing our new design;

FIG. 2 is a right-hand view thereof;

FIG. 3 is a left-hand view thereof;

FIG. 4 is front view thereof;

FIG. 5 is a rear view thereof;

FIG. 6 is a top view thereof;

FIG. 7 is a bottom view thereof;

FIG. 8 is another right-hand view thereof;

FIG. 9 is a cross-sectional view along line 9-9 shown in FIG. 8;

FIG. 10 is a cross-sectional view along line 10-10 shown in FIG. 8;

FIG. 11 is a cross-sectional view along line 11-11 shown in FIG. 8; and,

FIG. 12 is a cross-sectional view along line 12-12 shown in FIG. 8.

The broken lines illustrate portions of the Patmas weave stent that form no part of the claimed design.
